UNITED STATES PATENT OFFICE.

WILLIAM MCLEAN, OF LOS ANGELES, CALIFORNIA.

PROCESS OF LAYING PAVEMENTS.

SPECIFICATION forming part of Letters Patent No. 289,295, dated November 27, 1883.

Application filed August 17, 1883. (No model.)

To all whom it may concern:

Be it known that I, WILLIAM MCLEAN, a citizen of the United States, residing in the city and county of Los Angeles, and State of California, have invented a new and Improved Process of Laying Pavements, of which the following is a specification.

My invention relates to that class of pavements which are made up of various components usually in a comminuted form, called "concrete," and it has for its object to provide means whereby encaustic tiles and other ornamented or plain tiles and stones may be laid, in combination with any kind of concrete 15 to form sidewalks or other pavements.

To this end my invention consists in the process of making pavement, hereinafter described and claimed, reference being had to the accompanying drawing, which is a plan 20 view of a portion of sidewalk, illustrating my method of laying pavement.

The ground is first prepared in whatever manner may be required to suit the characteristics of the ground in that locality, and 25 the purpose for which the pavement, when laid, is to be used, the only requirement in this respect being that the ground be leveled to form a bed, allowing for the thickness of the concrete.

Suppose the pavement to be laid is for a sidewalk: Let A represent the curbstone or border, and B the building or inner line. Let C represent the commencing-line, and D the plank used to control the concrete and keep 35 the blocks E and F in place. Let E and F represent the triangular blocks used to form spaces for the insertion of tiles or concrete blocks of different colors or patterns, and to control the cracking or parting of the pavement; these blocks to be of the same thickness as the concrete portion of the pavement, and placed at such distances along the side of the plank and commencing-line as will 40 enclose a section to be worked, the width of the 45 plank to be of the thickness of the concrete to be laid. Now, fill the section with concrete mortar, H, work the surface smooth with trowel or other tool, and as soon as the concrete is sufficiently set remove the blank D

and blocks E and F, and plaster, coat, or wash 50 the edges of the pavement with common clay brought to the proper consistency, either with brush or other suitable tool, such as trowel, or the like. Now, in place of the blocks E, insert a square block, and in place of blocks 55 F insert triangular blocks E'. On the working side of the section place the plank D at the proper distance, with blocks E and F in line, and proceed with work as before.

It is intended that each section shall form 60 one inseparable piece, and that these non-cohesive partitions shall allow each section to shrink or change its level relative to contiguous sections without breaking the tiles or concrete blocks forming the sections H. 65

The spaces formed by removing the blocks E F and square blocks may be filled with concrete of any desired color, or with encaustic tiles of any desired pattern or color.

The use of the cross-plank D in forming 70 concrete is common, and the placing of blocks in the work is for the double purpose of allowing the ornamentation of the pavement itself, and to control the cracking of the concrete. Tiles of other forms than those shown 75 may be used, and the concrete portion of the pavement may be varied in form or color as fancy may dictate.

I am aware that concrete pavement has been made in sections parted from each other 80 by tarred paper; also, that vertically-tapering patterns have been surrounded, excepting only their top and bottom, by concrete, and removed after the concrete is set, to admit tiles shaped like said pattern, and I do not 85 claim the same as my invention.

What I claim as my invention, and wish to secure by Letters Patent, is—

The process of making pavement which consists in, first, placing upon a prepared 90 ground two or more straight-edges or other strips as boundaries for the first section of the pavement, one of which boundaries may be permanent; secondly, placing within and against these boundaries pattern-blocks, each 95 in the form of about one-half of the tile intended to take its place; thirdly, in filling the space between the boundaries thus formed

with concrete in the form of mortar, and allowing it to set; fourthly, in moving the boundary and the pattern-blocks to the distance required for another block of concrete; fifthly, 5 in placing tiles into the half-molds formed, allowing them to project into the space for the next block; sixthly, in thinly coating the edge of the block first formed with non-cohesive material; and, seventhly, in filling in

concrete between the boundary and half-patterns on the one side and the concrete and half the outlines of the tiles on the other, as shown and described.

WILLIAM McLEAN.
